UNITED STATES PATENT OFFICE

FRED J. LEWIS, OF INDIANAPOLIS, INDIANA, ASSIGNOR TO McLOUGHLIN MANUFACTURING COMPANY, OF INDIANAPOLIS, INDIANA

UNDERGARMENT

Application filed August 23, 1928. Serial No. 301,457.

This invention relates to underwear, and has for its primary object the cutting and forming of the waist to give the utmost comfort to the wearer particularly in that the 5 waist is reduced to the minimum covering area and yet is so formed and attached to the remainder of the garment as to prevent the supporting shoulder straps from sliding or working off the shoulders of the wearer. 10 Among the other objects of the invention are the provision of an undergarment which is exceedingly light in weight; the formation of the waist of a garment in such manner as to effect an economy of material; and the 15 provision of a garment wherein the waist is formed to cover a relatively small portion of the wearer's body, but at the same time is effectively and permanently secured to a waist-band, trousers member, or other lower portion thereof. 20

Other objects of the invention will in part be obvious and will in part appear herein-after.

The invention accordingly comprises an 25 article of manufacture possessing the features, properties, and the relation of elements which will be exemplified in the article hereinafter described and the scope of the application of which will be indicated 30 in the claims.

For a fuller understanding of the nature and objects of the invention reference should be had to the following detailed description taken in connection with the accompanying 35 drawing, in which:—

Fig. 1 is a front elevation of a garment embodying my invention;

Fig. 2, a rear elevation of the garment;

Fig. 3, a side elevation; and

Fig. 4, a developed top plan view of the 40 waist of the garment.

Like characters of reference indicate like parts throughout the several views.

The lower portion of the exemplified garment is formed in the usual manner with legs 45 5 and 6, a formed seat 7, and a drop flap 8. In the present instance, a belt 9 of non-yielding material is secured at the upper end of the trousers portion thus provided.

The waist or upper portion of the garment 50

is formed as is indicated in Fig. 4 with the two front straps 10 and 11, the two rear straps 12 and 13, the rear straps being connected to the front straps by means of a tie strap 14, which serves to unite these members and to prevent the waist portion from slipping off the shoulders of the wearer. 55

The lower or outer ends of the straps 10, 11, and 12, 13, are each flared out laterally to form bases 15, 16, 17, and 18, whereby 60 they may be secured to a lower or encircling portion such as exemplified by the belt 9. In order that the straps may be secured as firmly as possible to the belt 9, or other lower member, without unnecessarily covering the body 65 of the wearer, and in order that the entire garment, and particularly the waist, may be given the maximum strength consistent with the exposure of the greater portion of the upper part of the wearer's body, the straps 70 are rapidly flared laterally to an extent such that their lower or outer edges have a combined length substantially equal to the circumference of the belt 9, and the garment is formed with these outer edges meeting one 75 another on the line where the portions 15, 16, 17 and 18 join the belt 9. In the construction thus provided, the front, rear and side openings come to a point adjacent the belt 9. When spread out as in Fig. 4, the waist forms 80 a letter H, with the cross bar or tie strap 14 above the center so that it will be positioned across the upper back of the waist when assembled with the lower portion of the garment. As will be seen, the exemplified garment 85 is formed with a front opening through which the legs and hips of the wearer may be passed in putting on the garment, and which serves to leave exposed the entire neck and the greater portion of the front of the wearer's body. The garment is also formed with openings between the straps 10 and 12, and 11 and 13, respectively, which serve to leave exposed 90 the greater portion of the sides of the wearer's body, and a rear opening which leaves exposed much of the wearer's back. The garment does not circumferentially enclose the wearer at any point above the belt 9. 95

The strap 14 is comparatively narrow and resembles the letter I turned sidewise, and has 100

its ends elongated to be sewed to the ends of the respective straps 10, 11, and 12, 13. Thus the strap 10, the left-hand arm (Fig. 4) of the I-shaped strap 14 and the strap 12 form one shoulder strap of the garment; and the strap 11, the right-hand arm of the I-shaped strap, and the strap 13 form the other shoulder strap thereof. By a construction such as exemplified, wherein the cross strap is interposed between the front and rear straps, considerable economy of material is effectuated; since the front and rear straps may be laid cut on, and cut from, a piece of material, with the wide outer end of one strap contiguous to the narrow inner end of another, thereby reducing waste material to a minimum.

As will be seen from the drawings the waist is hemmed by four rows of stitching, indicated at 20, 21, 22 and 23, one defining the front opening, one defining the rear opening, and the other two defining the side openings. Besides hemming the edges of these openings, these stitches serve the purpose of reinforcing the connections between the front and rear straps and the cross-strap, and serve to prevent tearing at the points of connection. It will be noted that by the peculiar formation of the strap bases, the bases serve to assist in preventing the straps from slipping sidewise on the shoulders of the wearer and at the same time give a long connection of the straps with the belt 9, whereby a sturdy structure is provided but very little material is utilized in the waist to give the least possible coverage of the wearer. Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. An undergarment, comprising a laterally disposed I-shaped portion having divergent arms at each of its ends, a pair of straps extending from the arms of the I-shaped portion at one side thereof, a pair of relatively shorter straps extending from the arms of the I-shaped portion at the other side thereof, and an encircling portion to which the lower ends of said straps are secured.

2. An undergarment, comprising a cross-strap adapted to extend across the wearer's back; longitudinal straps extending in opposite directions from each end of the cross-strap, the cross strap and the longitudinal

straps being formed of separate pieces of material, and a line of stitching extending along the inner edge of one of said longitudinal straps, along the adjacent edge of the cross-strap, and along the inner edge of a longitudinal strap at the other end of the cross-strap; a line of stitching extending along the outer edge of the last mentioned longitudinal strap, the adjacent outer edge of the cross-strap, and the outer edge of the longitudinal strap extending in an opposite direction from the same end of the cross-strap, a line of stitching extending along the inner edge of the last mentioned longitudinal strap, the adjacent edge of the cross-strap and the inner edge of the remaining strap, and a line of stitching extending along the outer edge of the last mentioned strap, the outer edge of the cross-strap and the outer edge of the first mentioned longitudinal strap, said lines of stitching extending across the lines of connection of said cross-strap with said longitudinal straps and serving to reinforce the connections between the straps.

3. A union suit, comprising a trousers portion formed to provide a portion encircling the body of the wearer directly above the hips, and a waist portion formed of a pair of shoulder straps, each having flared lower ends attached to said encircling portion and being rapidly narrowed from their lower ends upwardly, and a cross strap arranged to retain said shoulder straps on the shoulders of said wearer, each of said shoulder straps being formed of front and rear sections united through the medium of one end of the cross strap interposed therebetween, each of said front and rear sections and said cross-strap being independent pieces of material, whereby unnecessary waste in cutting the garment is avoided.

In testimony whereof I affix my signature
FRED J. LEWIS.
